CLAIM

The ornamental design for a frame for air compressor, as shown and described.

DESCRIPTION

FIG. 1 is a perspective view of the frame for air compressor according to the present design;
 FIG. 2 is a left side view of the frame for air compressor as shown in FIG. 1;
 FIG. 3 is a right side view of the frame for air compressor as shown in FIG. 1;
 FIG. 4 is a top view of the frame for air compressor as shown in FIG. 1;
 FIG. 5 is a bottom view of the frame for air compressor as shown in FIG. 1;
 FIG. 6 is a rear view of the frame for air compressor as shown in FIG. 1; and,
 FIG. 7 is a front view of the frame for air compressor as shown in FIG. 1;
 The broken lines shown in the FIGS. 1-7 are included for the purpose of illustrating environment and form no part of the claimed design.
